UNITED STATES PATENT OFFICE.

JACOB HESSLER, OF CHICAGO, ILLINOIS, ASSIGNOR TO WILLIAM W. KIMBALL, OF SAME PLACE.

ORGAN-TREADLE.

SPECIFICATION forming part of Letters Patent No. 293,462, dated February 12, 1884.

Application filed November 2, 1881. (No model.)

To all whom it may concern:

Be it known that I, JACOB HESSLER, of Chicago, in the county of Cook and State of Illinois, have invented certain new and useful Improvements in Cabinet-Organ Treadles, 5 of which the following is a specification.

In the accompanying drawings, Figure 1 is a front view of the roller-bar of a cabinet-organ. Fig. 2 is a partial longitudinal section 10 of the same, and Fig. 3 is a transverse section on the line $x x$ of Fig. 2.

Similar letters of reference indicate similar parts.

In said drawings, A represents the roller-supporting bar; B B, the rollers, and C, one of the bands passing over the rollers and carrying power from the treadles to the bellows. The bar is cut away, so the rollers may be sunk entirely below its upper edge, as clearly shown, and it is 15 also passed longitudinally, for a portion of its length, over a circular saw, and thereby a kerf is formed which constitutes a seat for the pivots b of the rollers. Those portions of this kerf between the pivots are filled by the pieces 20 a , and after the rollers are in place the pivots are retained by plugs a' , permanently glued in the kerf above them. The sides of the roller-openings approach the rollers at the pivotal 25 points sufficiently close to form end bearings,

as seen at $o o$, preventing side-play by the 30 rollers without the use of washers or other devices for that purpose. Above and below the pivots the sides recede gradually from the rollers, whereby contact between the bands and bar is avoided except when the bands attempt to run off the rollers, and at such times the sides of the openings serve to keep them 35 in place.

I claim—

1. In a cabinet-organ, the roller-bar having 40 openings allowing the rollers to be sunk below its edge, and a longitudinal saw-kerf, furnishing a seat for the roller-pivots, in combination with the rollers having their pivots seated and secured in said kerf, and the bands passing 45 over said rollers, substantially as specified.
2. In a cabinet-organ, the roller-bar having cross-openings for the rollers, and a longitudinal saw-kerf for the pivots, the sides of the roller-openings approaching the rollers at the 50 pivotal points, substantially as and for the purpose set forth, in combination with the rollers.

JACOB HESSLER.
